ADJUSTABLE CAMERA MOUNTING PLATFORM

Neil D. Adams, Baton Rouge, La.
(R.R. 2, Ste. Genevieve, Mo. 63670)

Filed Oct. 12, 1971, Ser. No. 188,638

Term of patent 14 years

Int. Cl. D16—05

U.S. Cl. D61—1 G

FIG. 1.

FIG. 2.

FIG. 1 is a rear perspective view of an adjustable camera mounting platform showing my new design;

FIG. 2 is a front perspective view thereof with the mounting platform in a vertical position.

I claim:

The ornamental design for an adjustable camera mounting platform, substantially as shown and described.
